(57) **CLAIM**

The ornamental design for a LED package, substantially as shown and described.

DESCRIPTION

FIG. 1 is a perspective view from above the LED package in accordance with our design.

FIG. 2 is a left side elevational view of the LED package of FIG. 1 in accordance with our design. The right side elevational view is a mirror image of the left side elevational view.

FIG. 3 is a top plan view of the LED package of FIG. 1 in accordance with our design.

FIG. 4 is a front elevation view of the LED package of FIG. 1 in accordance with our design. The rear elevation view is a mirror image of the front elevation view; and,

FIG. 5 is a bottom plan view of the LED package of FIG. 1 in accordance with our design.

The broken lines showing an environment of the design are for illustrative purposes and form no part of the claimed design.
